UNITED STATES PATENT OFFICE.

CHARLES E. QUARNSTRÖM, OF CHICAGO, ILLINOIS, ASSIGNOR OF ONE-HALF
TO NELS P. HEDIN, OF SAME PLACE.

IRONING-MACHINE.

SPECIFICATION forming part of Letters Patent No. 472,954, dated April 12, 1892.

Application filed October 15, 1891. Serial No. 408,802. (No model.)

To all whom it may concern:

Be it known that I, CHARLES E. QUARNSTRÖM, a subject of the King of Sweden and Norway, residing at Chicago, in the county 5 of Cook and State of Illinois, have invented a new and useful Improvement in Ironing-Machines, of which the following is a specification.

My invention relates to an improvement in 10 ironing-machines of the class employed more especially for ironing and polishing shirt-bosoms, collars, and cuffs, and which involve as their main operating parts a hot revolving ironing or polishing roller and a support for 15 the article to be ironed reciprocating below and in contact with the ironing-roller.

My object is to provide a machine of the 20 above character of a simple, durable, and comparatively inexpensive construction and 25 which shall be eminently effective and quick in its operation.

In the drawings, Figure 1 is view of my improved machine in side elevation; Fig. 2, a 25 central longitudinal section of the same; Fig. 3, a section taken on line 3 of Fig. 1 and viewed in the direction of the arrow, and Fig. 4 a sectional plan view taken on line 4 of Fig. 1 and viewed in the direction of the arrow.

A represents the frame of the machine, comprising 30 two sides or castings t t' , connected together by cross-bars t^2 .

B is the drive-shaft, mounted in and extending through bearings s s' in the frame A. The shaft B carries at one end the fast pulley 35 r and two loose pulleys r' , and at its opposite end it is provided with a pinion q . Above and somewhat back of the shaft B is a shaft C in bearings in the frame A and carrying outside the frame a cog-wheel o , which meshes 40 with the pinion q . Between its bearings the shaft C carries a friction wheel or drum C', the outer circumference of which affords a friction-surface.

D is a swinging frame comprising side bars 45 n n , connected together at their end portions by cross-bars n' . The side bars n n are rabbed in their adjacent faces to afford a grooved track n^3 , as shown in Fig. 3. The frame D is supported on arms or brackets n^2 ,

rigid therewith and which are pivotally mounted 50 at their lower ends on the shaft C between the drum C' and sides of the frame A. Journaled in bearings m , extending downward from the side bars n of the frame D, is a roller m' . Extending downward from the 55 center of the cross-bar n' , nearest the front of the machine, is a lug l , threaded at its lower end, and extending downward from the cross-bar l^2 at the forward end of the frame A is a lug k , threaded along its lower end 60 portion. A bracket i of the angular shape shown in Fig. 2 is provided near its opposite ends with openings which fit, respectively, closely, but loosely, over the lugs l k . Interposed between the bracket i and bar n' on the 65 lug l is a cushion l' , which may be of rubber, as indicated by the drawings, or any convenient form of spring, and the bracket i is maintained against the cushion by a nut l^2 on the threaded end of the lug l . Surrounding the 70 lug k and confined between the bracket i and cross-bar l^2 is a spring k' . Below the bracket i on the threaded portion of the lug k is a crank k^2 . Turning of the crank k^2 in one direction causes it to travel up the lug k , and 75 by bearing against the bracket i carrying the latter up against the resistance of the spring k' . The bracket i in its rise lifts the frame D and swings it upward on its pivot, which, as before stated, is the shaft C. Turning of 80 the crank k^2 in the other direction causes it to travel downward on the lug k and permit the frame D to swing downward on its pivot.

The reciprocating ironing-board frame or support E for the goods comprises a base-board 85 h , centrally upon which is mounted the ironing-board proper E'. At the sides of the base h are flanged upwardly-extending plates h' .

F is a hollow ironing or polishing roller mounted near opposite ends in bearings g g' 90 at the tops of the sides t t' , respectively, of the frame A. Outside the bearing g' the ironing-roller carries a pinion f , which meshes with the cog-wheel o . Extending into the roller F is a gas-burner x . The drum C' and roller m' extend at the highest points of their circumferences in a plane about one-eighth of an inch above the guide-grooves n^3 .

in the side bars n , and the base-board h of the reciprocating ironing-board frame, which slides in the grooves n^3 , rests upon the drum C' and roller m' . The ironing-roller F is 5 mounted slightly forward of the shaft C and back of the roller m' .

G is belt-shifting mechanism, comprising the shifter e , which engages the belts and which is connected by rods e' with a sliding 10 collar e^2 on the shaft B . Mounted in a bearing f^3 at the center of the lower forward cross-bar f^2 of the frame A is a vertical rod e^3 , to the upper end of which is keyed a backward-extending arm e^4 . At its opposite end the arm 15 e^4 is connected pivotally to the collar e^2 . Adjustable up and down on the rod e^3 is a cross-bar e^5 , formed at opposite ends with foot-rests e^6 . The cross-bar e^5 may be secured in adjusted position by a set-screw e^7 , which thus 20 operates, also, to fix the bar e^5 against independent rotation upon the rod e^3 .

The shaft B is rotated from a suitable driving-power by belts, one of which is crossed, so that when they are shifted alternately to 25 the fixed pulley r they will rotate the latter in opposite directions.

In operation the ironing-board is slid forward out of engagement with the drum C' and the article to be ironed placed thereon. The 30 belt-shifting mechanism is turned by the operator with his feet to cause the drum C' to rotate in a direction which will cause it to carry the ironing-board in the backward direction when the latter is pushed backward 35 into engagement therewith. The frame D is adjusted upon its pivot by turning the crank k^2 to cause the upper surface of the ironing-board to engage the ironing-roller F . The operator then pushes the ironing-board frame 40 in a backward direction until it is engaged by the drum C' , which, owing to its frictional engagement with the under side of the base-board h , carries the ironing-board in the backward direction. When the ironing-board 45 has passed under the roller F , the operator by turning the cross-bar e^5 with his feet will shift the other belt to the fast pulley r and cause the motion of the drum C' to reverse and slide the ironing-board in the forward direction. The ironing-board may thus be 50 reciprocated backward and forward until the article carried by it is suitably ironed. By simply turning the crank k^2 the pressure of the ironing-board against the ironing-roller 55 may be regulated at will. To prevent the ironing-board frame from being caused to travel too far in either direction, I fasten it at its forward end by means of a chain or other flexible medium d , of suitable length, to the 60 upper forward cross-bar f^2 .

As the frame D is pivoted upon the shaft C , the drum C' will always project the same distance above the lower sides of the grooves n^3 . Owing to the relative positions of the 65 drum C' and ironing-roller F , the adjustment of the frame D on its fulcrum to regulate the

pressure of the ironing-board against the roller F is under perfect control of the operator and may be quickly changed at will.

The operator may sit down, if he desires, 70 while operating the machine, and the cross-bar e^5 may be raised and lowered to suit his convenience.

I do not claim the belt-shifting mechanism 75 in this application.

Some articles have to be ironed under a great pressure to produce the best results, and, owing to the frame D being pivoted on the shaft C and the relative position of the ironing-roller, much greater leverage comparatively may be had than were the frame D pivoted at the back of the machine, as is usual in machines of this class. In my improved machine, furthermore, the relative positions of the cog-wheel o and pinions q and f are 80 never changed. In those ironing-machines wherein the shaft C is journaled in the swinging frame D the teeth of the cog-wheels have necessarily to be considerably longer than in my machine to compensate for the swinging 85 of the frame D , and as a consequence of the teeth being long they mesh loosely and there is a constant rattling of the gears in their operation which it is desirable to overcome and which is not present in my machine. 90

What I claim as new, and desire to secure by Letters Patent, is—

1. In an ironing-machine, the combination, 100 with the main frame and support for the goods, of a rotating shaft C , a friction-wheel C' on the shaft C , a swinging frame D , in which the said support is mounted to reciprocate, pivoted on the shaft C , ironing-roller F above the shaft C , the center of the roller F being to one side of a line perpendicular to the 105 plane of the path of the said support and passing through the center of the shaft C , and means for swinging the frame D on its pivot, substantially as described.

2. In an ironing-machine, the combination, 110 with the main frame A , of a drive-shaft B , shaft C , and ironing-roller F , journaled in the frame A , the center of the roller F being to one side of a line perpendicular to the plane of the path of the support for the goods 115 and passing through the center of the shaft C , a cog-wheel o on the shaft C , pinions q and f on the shaft B and roller F , respectively, engaging the said cog-wheel, friction-wheel C' on the shaft C , swinging frame D , pivoted on the shaft C , reciprocating support for the goods 120 in the frame D , resting on the wheel C' , and means for raising and lowering the frame D on its pivot, substantially as described. 125

3. In an ironing-machine, the combination, 125 with the main frame and reciprocating support for the goods, of a rotating shaft C , a swinging frame D , pivoted on the shaft C , guideways n^3 in the frame D for the said support, a friction-wheel C' on the shaft C , and a roller m' on the frame D , engaging the said support, ironing-roller F , journaled in the 130

frame A, the center of the roller F being to one side of a line perpendicular to the plane of the path of the said support and passing through the center of the shaft C, and means for raising and lowering the frame D on its pivot, comprising the lug l on the frame D, spring l' on the lug l, threaded lug k on the

frame A, bracket i, sliding on the lugs l k, and traveling crank k² on the lug k, substantially as described.

CHARLES E. QUARNSTRÖM.
